UNITED STATES PATENT OFFICE.

HENRY F. GOETZ, OF WATERBURY, CONNECTICUT, ASSIGNOR TO WATERBURY MFG. CO.,
OF WATERBURY, CONNECTICUT, A CORPORATION.

FUSE-PLUG.

1,282,566.

Specification of Letters Patent.

Patented Oct. 22, 1918.

Application filed May 6, 1918. Serial No. 232,749.

To all whom it may concern:

Be it known that I, HENRY F. GOETZ, a citizen of the United States, residing at Waterbury, in the county of New Haven and State of Connecticut, have invented a new and useful Improvement in Fuse-Plugs; and I do hereby declare the following, when taken in connection with the accompanying drawings and the characters of reference marked thereon, to be a full, clear, and exact description of the same, and which said drawings constitute part of this application, and represent, in—

Figure 1 a view in side elevation of a fuse-plug constructed in accordance with my invention.

Fig. 2 a view thereof in central longitudinal section on the line 2—2 of Fig. 1.

Fig. 3 a reverse plan view thereof.

Fig. 4 a detached plan view of the cupped sheet-metal contact.

Fig. 5 a view thereof in side elevation.

Fig. 6 a corresponding view taken at a right angle to Fig. 5.

Fig. 7 a sectional view on the line 7—7 of Fig. 4.

My invention relates to an improved fuse-plug for electrical purposes, the object being to produce at a low cost for manufacture, fuse-plugs of superior efficiency due to the employment of sheet-metal contacts of special construction, whereby their correct seating in the plug-body is assured.

With these ends in view, my invention consists in a fuse-plug having certain details of construction as will be hereinafter described and pointed out in the claim.

In carrying out my invention, I employ an ordinary chambered porcelain body 8 formed at its outer end with a beveled concentric flange 9 over which is clasped a sheet-metal cap 10 having a concentric sight-opening 11 for the exposure of the central portion of a transparent mica disk or closure 12 held in place by the cap in the usual manner. The said flange is formed with an inclined passage 13 leading into the chamber 14 of the plug, the interior of this chamber being visible through the said mica disk 12. The passage 13 receives a connecting strip 15 the outer end of which is soldered at 16 to the outer edge of a screw-shell 17 which surrounds the body 8 of the plug, the said body being molded with threads 18 for the

retention of the shell 17 in place. The inner end of the strip 15 has soldered to it at 19 the outer end of a fuse wire 20 the inner end of which is bent at 21 and hooked under and soldered as at 22 to one of the two complementary arms 23 of a sheet-metal contact 60 mounted in a small circular concentric passage 24 formed in the rounded inner end of the body 8. The said contact, which is made of a single piece of sheet-metal, comprises the complementary arms 23 aforesaid, 65 and a shallow, circular cup 25 having a bearing-flange 26 the full circumference of which is seated upon the outer face of the rounded end of the plug-body 8. The said flange 26 is at least equal in depth to the thickness of the sheet-metal from which the contact is made, so that it will fully accommodate the horizontally arranged butt-ends or reaches 27 of the arms 23 which are bent inwardly from opposite points on the flange 75 26 which is thus permitted to bear throughout its entire circle directly upon the outer face of the inner end of the body 8 since the cup 25 being at least as deep as the thickness of the reaches 27, receives the same and 80 so leaves their outer ends flush with the edge of the flange. The arms 23 as they rise from the reaches 29 are made concavo convex in cross section so that their outer faces will fit into and conform to the walls of the 85 hole 24. The arms of the contact are sprung apart and have their outer ends outwardly upset, after the contact is inserted into the hole 20 as shown in Fig. 2, whereby the contact is retained in place. On account of its 90 construction, the contact seats itself in the plug body so that its outer face will entirely lie in a plane at a right angle to the axis of the plug, whereby a perfect contact is assured, whereas if the contact is tilted in the 95 plug as is often the case with the contacts now in use, only the high spots, so to speak, on its outer face will be engaged, and a poor contact will result.

I claim:—

In a fuse-plug, the combination with the porcelain body thereof, of a cap applied thereto, a transparent closure held in place by the said cap, a threaded shell applied to the said body, a sheet-metal contact mounted in a concentric opening in the inner end of the body and comprising a shallow, circular cup and two arms, the said cup being

formed with a bearing-flange equal in depth to the thickness of the metal for the reception of the horizontal butt-ends or reaches of the said arms, a fuse having its inner end soldered to one of the said arms of the contact, and a connecting strip between the outer end of the said fuse and the said shell.

In testimony whereof, I have signed this specification in the presence of two subscribing witnesses.

HENRY F. GOETZ.
